UNITED STATES PATENT OFFICE.

PAUL F. LINDEN, OF YONKERS, NEW YORK.

IDENTIFICATION SEAL.

Application filed December 27, 1927. Serial No. 242,699.

This invention relates to identification seals for use in connection with merchandise such as fur, cloth, hats, fabrics and other materials and merchandise of the character which is usually handled, or is likely to be handled by various persons or concerns during the manufacture thereof, and in which it is likely that the raw fur or other goods in the course of being tanned, dyed or bleached may become confused or co-mingled with other goods rendering it likely that exchanges of goods could or would be made thus, resulting in losses to the owner of the goods and the object of my invention is to produce such an identification means as will prevent such losses.

Furthermore, the object of the invention is to produce an identification or protective seal possessing a separate master plate, whereby furriers may safely send raw furs, skins and the like out to tanners and finishers without undergoing the risk of having cheaper or inferior grades of furs and merchandise substituted for their own merchandise.

Heavy losses occur annually to furriers due to that fact that they possess no positive satisfactory means of protection against the substitution of inferior skins during the process of treating, finishing, defleshing and tanning of skins, for the raw fur and finished product appears in such a contrasted state as regards color, texture, appearance and weight, that the owner of a tanned skin cannot successfully show that the finished product is not in fact the original fur.

Regarding textiles, as in the final stages of manufactured silk goods and particularly when it comes to the dyeing of goods in the bolt, losses frequently occur which are often-times fraudulently explained by the fact that the goods drew up by shrinkage and that the linear measurement of the goods in the bolt comes one or two yards short by reason of such shrinkage, whereas in fact the loss in yardage of silk or other cloth occurs by reason of that fact that a portion of the end of the bolt is cut off and removed by irresponsible persons, and in this connection it is an object of my invention to provide an identification seal capable of being affixed to each end of the cloth in the bolt whereby the cutting off of either end thereof would correspondingly remove the seal from the cloth, thus revealing to the true owner the fact that his losses are due to reprehensible practices against him and his property.

Furthermore, it is an object of the invention to provide a protective seal embodying a master plate which remains in the possession of the owner of the merchandise and by which he quickly discovers losses, if any when the goods are returned to him.

The invention is not limited to the structure and use as hereinafter described, but certain changes may be made without departing from the scope of the invention as defined in the appended claims.

Fig. 1 shows a remnant of fur or other merchandise with my improved identification seal affixed thereto.

Fig. 2 shows the master plate as embodied in my improved identification seal.

Fig. 3 is a similar view to that shown in Fig. 1 illustrating the master plate as embodied in my improved identification seal.

Fig. 4 is an enlarged longitudinal sectional view taken on the line 4—4 of Fig. 1.

Fig. 5 is a longitudinal sectional view of the identification seal before it has been affixed to the merchandise.

Fig. 6 is a sectional view similar to Fig. 4 but illustrating a modification of the invention.

Fig. 7 is a view similar to Fig. 6, but illustrating another modification.

My improved identification seal may be manufactured of any suitable light weight material, such as aluminum alloy, white metal, brass, copper, which is readily and easily drawn or extruded by a punch press, or automatic metal working machine.

As here embodied the improved identification seal consists of a piece of metal 10 preferably rectangular, having its extremities rounded, and having wedged in, punched, drawn, or extruded locking and riveting heads 11 and 12 positioned in proximity to the rounded extremities thereof. The plate member 13 is substantially of the same shape as the above mentioned and described piece of metal and has formed therein apertures 14 and 15 suitably positioned to receive the heads 11 and 12 which are projected through the apertures 14 and 15 when the seal is affixed to the skin or other merchandise. The heads are riveted down to permanently attach the seal to the fur.

The master plate 16, preferably made of any of the hereinbefore mentioned soft metals is of square or rectangular shape and has formed therein a plurality of openings 17, or

apertures, adapted to receive the improved identification seal, as clearly shown in Fig. 3 of the accompanying drawing. The identification seal is provided with a serial letter 18 such as A, B, C, etc., which are important marks which enable the owner to quickly pick his particular master plate upon receipt of the goods, the corresponding master plate being provided with the same serial letter 19. The master plate 17 is provided with the serial numbers 20 and 21, which are the numbers of the first and last openings formed therein, and which may be readily located from the number 22 placed at the right of each row of the said openings 17. The corresponding numbers are provided on the corresponding seal, as at 23. The latter described numbering is such as will readily permit the owner of the merchandise to which the improved seal is affixed to locate the corresponding opening of the master plate. The identification seal and the master plate are provided with identification marks 24 and 25, respectively, positioned at the edges thereof and formed separately, but simultaneously on the seal and on the master plate.

The identification marks consist preferably of a series of parallel radiating lines stamped upon the seal and the master plate, which enables the owner of the merchandise to which the seal is affixed to positively identify the merchandise to which the seal is affixed, as the identification marks on the seal and master plate will match up or mate by reason of the fact that the identification marks were applied to the seal and to the master plate at the same time. Preferably, no two seals will bear the same identification marks. The owner of the goods retains the master plate in his possession when he makes shipment of the merchandise to the tanners and finishers.

The modification of the invention illustrated in Fig. 6, discloses a plate member 13' having integral converging sides 13^a. Sealing material 13^b is poured into the pocket formed by the sides 13^a, and a signet ring impression 13^c is formed on the face of the sealing material before it hardens. The sealing material may be sealing wax, or some metal having a low melting point. The converging sides 13^a prevent the removal of the material 13^b which in turn obviates the possibility of fraudulent persons bending open the riveted ends of heads 11 and 12 to replace the seal 10 on other material. The plate 13' and sides 13^a are of very brittle material, preferably cast, and would rather break than bend.

Fig. 7 discloses the rivet heads 11 and 12 provided with a plurality of pivoted ends 26, normally urged to inclined positions by springs 27 co-axially arranged on the pivots and acting between the rivet heads and the end 26. Sealing material 28 is poured onto the plate 13 and covers the ends 26 the face of

the sealing material being provided with a signet ring impression 29.

It is obvious from the foregoing description that I have produced identification seals bearing identification marks which are physically impossible for the tanner or finisher to copy, which will eliminate and discourage the practice of fraud and any attempt to duplicate or copy my improved seals.

Having thus described my invention, what I claim as new and desire to protect by Letters Patent of the United States is as follows:

1. An identification seal of rectangular shape having its extremities rounded and having locking heads adapted to project through apertures formed in a plate member, as a means of affixing the said seal to a piece of merchandise, said seal provided with identification marks, corresponding identification marks provided on a master plate, said corresponding identification marks affixed at the edges of an opening formed in the said master plate, as a means of positively identifying the said seal.

2. An identification seal of rectangular shape having its extremities rounded and having locking heads adapted to project through apertures formed in a plate member, as a means of affixing the said seal to a piece of merchandise, said seal provided with identification marks, corresponding identification marks provided on a master plate, said corresponding identification marks affixed at the edges of an opening formed in the said master plate, as a means of positively identifying the said seal, corresponding serial letter and serial numbers affixed to the said seal and to the said master plate, as a means of readily bringing the said seal and the said master plate together.

3. An identification seal of rectangular shape having its extremities rounded and having locking heads adapted to project through apertures formed in a plate member, as a means of affixing the said seal to a piece of merchandise, said plate being formed with integral converging sides, and sealing material poured therein and formed with a signet impression.

4. An identification seal of rectangular shape having its extremities rounded and having locking heads adapted to project through apertures formed in a plate member, as a means of affixing the said seal to a piece of merchandise, the said locking heads being provided with pivoted ends urged into inclined positions by springs, and sealing material engaged over the said plate member, and the inclined ends of the locking heads.

In testimony whereof I have affixed my signature.

PAUL P. LINDEN.
